DYEING APPARATUS

Donato Greco, Amsterdam, N. Y.

Application August 28, 1933, Serial No. 687,213

6 Claims. (Cl. 8—19)

The object of the invention is to provide a frame for use in connection with dyeing machines employed for dyeing yarn in the skein, so that the skeins may be readily lowered in the dyeing vat and removed therefrom without the necessity for the operator or other workmen having to enter the vat with the hazards, such as the possibility of an overhanging weight falling, which attend such action; to provide a frame for skein dyeing apparatus which will maintain positively a definite spaced relation of the skein hangers during the dyeing operation, so that when the skeins are removed, they may be placed on a truck adapted to receive the skein hangers and maintain the relation which they have when mounted in the frame; and generally to provide a device of the kind indicated which is of comparatively simple form and susceptible of cheap manufacture.

With this object in view, the invention consists in a construction and combination of parts of which a preferred embodiment is illustrated in the accompanying drawings but to which embodiment the invention is not to be restricted.

Continued use in practice may dictate certain changes or alterations and the right is claimed to make any which fall within the scope of the annexed claims.

In the drawings:

Figure 1 is a side elevational view of a frame constructed in accordance with the invention and the trucks in connection with which the frame is used.

Figure 2 is an end elevational view of the same.

Figure 3 is a top plan view.

Figure 4 is a view similar to Figure 2 but showing the arrangement after skein hangers have been delivered to the trucks.

Figure 5 is a sectional view on the plane indicated by the line 5—5 of Figure 1.

Figure 6 is a detail elevational view, partly in section, of the truck carried skein hanger support.

Figure 7 is a perspective view of one of the skein hangers employed.

The invention comprises a frame 10 made preferably of timbers and incorporating a vat cover 11 formed of boards spanning the frame and arranged in edge-abutting relation, so that when the frame is lowered into the vat, the boards may constitute a cover for the latter. All of the boards are laid directly on the frame and secured thereto with the exception of the terminal boards 12 which have hinged connections 14 with the

next adjacent boards. When the frame is in position in the dyeing vat, therefore, the terminal boards or leaves 12 lie at opposite ends of the vat and may be elevated to permit observation of the interior.

The frame is lowered into and raised from the vat mechanically by any acceptable means and to permit its being handled it is provided, above the top or cover 10, with the crossbars 15, these being preferably metallic channel members through the flanges of which extend the eye bolts 16 disposed near the extremities of the bars and having their eyes engaged with the hook bolts 17 carried by the frame. The bars 15 are disposed at intermediate points in the length of the frame and at their longitudinal centers carry the plates 18 which project enough above the upper edges of the bars to provide ears with which the chains 19 are connected, the chains being united by means of a common link 20 with which the hoist- 75 ing and lowering apparatus may be connected.

The frame, on the under side, is provided with the longitudinal rails 21, in the under edges of which are formed notches to serve as seats for the skein hanger bars 22 which are of cross-sectionally oval form as shown in Figure 7 but which on one longitudinal edge and at the ends are cut away to leave flat faces to serve as seats for the grouping bars 23. The grouping bars 23 are seated in the hooks of J-bolts 24 which are slidably mounted in the openings formed in the frame 10 and which have their shanks threaded at the ends remote from the hooks to threadingly engage the eyes of hand wheels 25, the hand wheels being laterally seated on the upper ends of guide sleeves 26, flanged, as at 27, with the flanges drilled to receive lag screws 28 by which the guide sleeves are secured to the frame 10. The shanks of the J-bolts at their upper extremities are provided with the handles 29 by means of which the shanks 95 are prevented from turning, when the hand wheels 25 are rotated. The handles and the hand wheels thus serve as means for imparting axial movement to the J-bolts while precluding angular or turning movement of the same in the 100 openings in the frame through which they pass.

With the skeins of yarn looped over the skein hangers, the latter are seated in the recesses or notches in the rails 21 with the flat faces at the ends disposed downwardly, the grouping bars 105 being carried in the hooks of the J-bolts 24 and the skein hangers having their flat faces at the opposite ends resting on these grouping bars. After all the skein hangers are inserted in their particular seats, the J-bolts are tightened by ro- 110

tating the hand wheels 25, this tending to move the grouping bars in the direction of the side rails 21 and effect a gripping action on the skein hangers in their seats. The whole frame may 5 then be lowered into the dyeing vat, when the skein becomes immersed in the dye. After immersion for the desired length of time, the frame is elevated out of the vat and transported in the customary manner to deposit the skein hangers 10 and their contents in trucks to be transported to appropriate places for drying. The trucks employed to receive the skein hangers are of open frame construction, being constructed preferably of pipe sections to provide an open frame 30, the 15 upper side rails of which are provided with laterally extending hooks 31 constituting supports for the grouping bars. The side rails of the truck frame have secured thereto the plates 32 which are notched in the upper edges as indicated at 20 33 to provide skein hanger seats which are spaced in accordance with the spacing of the seats in the frame rails 21. The plates 32 are secured to the upper side rails of the frame 30 by the shanks of the hooks 31 which are threaded, as indicated at 25 34, and which extend transversely through the truck frame rails and through the plates, nuts 35 being threaded on the shanks of the hooks to abut the truck frame rails on one side and nuts 36 being attached to the extremities of the hook 30 shanks, to bear against the plates 32 and hold them in lateral contact with the truck frame rails.

In moving the frame 10 from the dyeing vat, it is disposed over the trucks and lowered until the grouping rails seat in the hooks 31, when the 35 skein hangers will enter the notches 33. The grouping rails and skein hangers are then released from the frame 10 by rotating the hand wheels 25 in a direction to effect lowering of the hooks or longitudinal movement in the direction 40 opposite from the former direction of movement. After having been lowered sufficiently, they may be turned angularly to free them from the grouping rails, when the frame 10 may be elevated for the reception of other grouping rails and skein 45 hangers with their contents.

The invention having been described, what is claimed as new and useful is:

1. Dyeing apparatus comprising a frame, J-bolts extending downwardly through the frame, 50 grouping bars seated in the hooks of the J-bolts, and skein hangers resting on the grouping bars and arranged in spaced relation along the latter.

2. Dyeing apparatus comprising a frame, J-bolts extending downwardly through the frame,

55

grouping bars seated in the hooks of the J-bolts, and skein hangers resting on the grouping bars and arranged in spaced relation along the latter, the frame being formed on the under side with spaced seats for the skein hangers.

80

3. Dyeing apparatus comprising a frame, J-bolts extending downwardly through the frame, grouping bars seated in the hooks of the J-bolts, and skein hangers resting on the grouping bars and arranged in spaced relation along the latter, the J-bolts being provided with means for effecting axial adjustment of the same to impose gripping action on the skein hangers jointly by the grouping bars and frame.

85

4. Dyeing apparatus comprising a frame, J-bolts extending downwardly through the frame, grouping bars seated in the hooks of the J-bolts, and skein hangers resting on the grouping bars and arranged in spaced relation along the latter, the J-bolts being provided with means for effecting axial adjustment of the same to impose gripping action on the skein hangers jointly by grouping bars and frame, the frame on the under side being formed with spaced seats for the reception of the skein hangers.

90

5. Dyeing apparatus comprising a frame, J-bolts extending downwardly through the frame, grouping bars seated in the hooks of the J-bolts, and skein hangers resting on the grouping bars and arranged in spaced relation along the latter, the J-bolts being provided with means for effecting axial adjustment of the same to impose gripping action on the skein hangers jointly by the grouping bars and frame, the adjusting means for the J-bolts consisting of hand wheels 105 threadingly engaged with the shanks of said bolts, and means to preclude angular or turning movement of the bolts.

100

6. Dyeing apparatus comprising a frame, J-bolts extending downwardly through the frame, 115 grouping bars seated in the hooks of the J-bolts, and skein hangers resting on the grouping bars and arranged in spaced relation along the latter, the J-bolts being provided with means for effecting axial adjustment of the same to impose gripping action on the skein hangers jointly by the grouping bars and frame, the adjusting means for the J-bolts consisting of hand wheels 120 threadingly engaged with the shanks of said bolts, and means to preclude angular or turning movement of the bolts and consisting of lateral projecting handles at the upper extremities of the shanks.
